UNITED STATES PATENT OFFICE.

MICHAEL J. LEARNIHAN, OF KANSAS CITY, MISSOURI.

PLUMB-BOB-SUPPORTING MECHANISM.

Application filed March 19, 1923. Serial No. 626,030.

To all whom it may concern:

Be it known that I, MICHAEL J. LEARNIHAN, a citizen of the United States, residing at Kansas City, in the county of Jackson and State of Missouri, have invented a certain new and useful Improvement in Plumb-Bob-Supporting Mechanism, of which the following is a specification.

My invention relates to improvements in plumb bob supporting mechanisms. It relates particularly to a mechanism which employs a plumb bob.

One of the objects of my invention is to provide a plumb bob supporting mechanism which is simple, cheap to make, durable, not liable to get out of order, which may be readily and quickly operated for obtaining a plumb line through a floor or ceiling, which can be readily operated by one person, and which eliminates the necessity of going to a floor above to obtain a plumb line through a hole in said floor.

The novel features of my invention are hereinafter fully described and claimed.

In the accompanying drawing, which illustrates the preferred embodiment of my invention,

Fig. 1 is a side elevation, of my improved mechanism, shown mounted on a floor and supporting a plumb bob.

Fig. 2 is an enlarged view, partly in elevation and partly in vertical section of my improved mechanism, the supporting members being shown in solid lines in the release or vertical position, and in dotted lines in the supporting position.

Fig. 3 is a view similar to Fig. 2 taken at right angles to the position shown in Fig. 2.

Fig. 4 is a top view of what is shown in Fig. 2.

Similar reference characters designate similar parts in the different views.

1 designates a fulcrum member which may comprise a vertical tube having a closed bottom 2, provided with a vertical central hole 3, Fig. 2. The member 1 is provided at its upper end with two upwardly extending arms 4, through which extends a horizontal pin 5, on which are pivoted adjacent to their lower ends two supporting members 6 and 7, which are held spaced apart by a washer 8, mounted on the pin 5.

It will be noted that the members 6 and 7 have their centers of gravity disposed at opposite sides respectively of the pin 5, whereby the members, when free so to do, will

swing by gravity in opposite directions from the vertical position, shown in solid lines in Fig. 2, to the horizontal position, shown in dotted lines in said figure. When the members 6 and 7 are vertically disposed, they with the fulcrum member 1 can be inserted into and through a hole 9 in a floor or ceiling 10. If the members 6 and 7 are then permitted to fall, they will swing in opposite directions from the vertical to the horizontal position, thus resting on the floor. To hold the members 6 and 7 in either the vertical position or in the horizontal position, there is slidably mounted in the member 1 a holding member 11 which is supported on the upper end of a coil spring 12, the lower end of which rests on the bottom 2 of the fulcrum member. The spring 12 normally forces the holding member 11 against the members 6 and 7. When said members are vertical, the member 11 bears against the flat lower edges of said members, and when the latter are horizontal, the member 11 bears against the lower side edges of the members 6 and 7.

For releasing the members 6 and 7 from engagement with the holding member 11, the upper end of a flexible supporting member 13 is attached to the member 11, said member extending downwardly through the coil spring 12 and through the hole 3. The lower end of the member 13 supports a plumb bob 14, which may be provided with the usual friction restrained drum 15 to which the member 13 is attached and on which said member is adapted to be wound.

In the operation of my invention, the members 6 and 7 are disposed in the vertical position shown in solid lines in Figs. 2 and 3, and then inserted upwardly through the hole 9 in the floor or ceiling 10 above, after which the flexible member comprising a cord or wire 13 is pulled downwardly, while the fulcrum member 1 is held stationary, thus withdrawing downwardly from engagement with the lower ends of the members 6 and 7, the holding member 11. The members 6 and 7 will then swing by gravity from the vertical position shown in solid lines in Figs. 2, 3 and 4, to the horizontal position against the floor, as shown in solid lines in Fig. 1, and in dotted lines in Figs. 2 and 4. The downward pull on the flexible member 13 is then removed, thus permitting the spring 12 to force the member 11 against the lower edges of the members 6 and 7, thus holding

the latter in the horizontal position, in which position they will support the remainder of the mechanism. The plumb bob 14 may then be used in the ordinary manner. After 5 the plumb line has been established, the device may be withdrawn from engagement with the floor above, by pulling downwardly on the flexible member 13, thus withdrawing the holding member 11 out of engagement 10 with the members 6 and 7, upon which, by pulling downwardly on the member 1, the members 6 and 7 will fold upwardly to the vertical position, in which position they can be readily pulled downwardly through the 15 hold 9 for use elsewhere.

Ordinarily in plumbing through a hole which extends through the floor and ceiling, it is necessary for some one to go from the floor below to attach and release the plumb 20 line which extends through the hole in the floor and ceiling. In such case, an additional operator is required located on the floor above, or, if there is but one operator, he has to make two trips to the floor above 25 to attach and release the plumb line. With the use of my invention, but one operator is needed and he can run the different plumb lines through the floor above without having to make any trips to that floor.

30 Any desired type of plumb bob may be used in connection with my plumbing mechanism, the one shown being one with a common type of cord take-up.

I do not limit my invention to the structure shown and described, as many modifications, within the scope of the appended claims, may be made without departing from the spirit of my invention.

What I claim is:—

40 1. In a plumb bob supporting mechanism, a fulcrum member, two supporting members having means pivotally connecting them to said member by which they may swing by gravity in opposite directions respectively 45 from the perpendicular to the horizontal, releasable holding means for holding said members in either the horizontal or the vertical position, plumb bob supporting means engaging said holding means and arranged 50 when moved in one direction, to release the holding means from said supporting members, and means for automatically retracting said holding means to the holding position, substantially as set forth.

55 2. In a plumb bob supporting mechanism, a fulcrum member, two supporting members having means pivotally connecting them to said member by which they may swing by gravity in opposite directions respectively 60 from the perpendicular to the horizontal, spring actuated holding means supported by said member and arranged to engage said supporting members for holding them in either the horizontal or the vertical position, 65 and plumb bob supporting means engaging

said holding means and arranged when moved in one direction to release said holding means from said supporting members, substantially as set forth.

3. In a plumb bob supporting mechanism, 70 a fulcrum member, two supporting members having means pivotally connecting them to said member by which they may swing by gravity in opposite directions respectively from the perpendicular to the horizontal, a 75 holding member longitudinally movable on said fulcrum member and arranged to engage and releasably hold said supporting members in either the horizontal or the vertical position, a spring supported by said 80 fulcrum member and engaging and normally forcing said holding member to the holding position, and plumb bob supporting means attached to said holding member and adapted when moved in one direction to 85 withdraw said holding member from the holding position, substantially as set forth.

4. In a plumb bob supporting mechanism, 90 a fulcrum member, two supporting members having means pivotally connecting them to said member by which they may swing by gravity in opposite directions from the perpendicular to the horizontal, said fulcrum member having means arranged to hold each supporting member from swinging by 95 gravity in one direction only, releasable means for holding said supporting members in either the horizontal or the vertical position, means for automatically retracting said holding means to the holding position, 100 and plumb bob supporting means supported by said fulcrum member, substantially as set forth.

5. In a plumb bob supporting mechanism, 105 a fulcrum member, two supporting members pivoted thereto so as to swing by gravity in opposite directions respectively from the perpendicular to the horizontal, each supporting member having means for being held by the fulcrum member from swinging 110 in one direction only to the horizontal, a holding member vertically slidable on the fulcrum member and arranged to engage and hold the supporting members in either the horizontal or the vertical position, a 115 spring supported by said fulcrum member and engaging and holding the holding member in the holding position, and plumb bob supporting means attached to and adapted to be supported by said holding member and adapted when moved in one direction to withdraw the holding member from engagement with said supporting members, substantially as set forth.

6. In a plumb bob supporting mechanism, 120 a fulcrum member having a vertical hole, two supporting members pivoted to said fulcrum member and arranged to swing by gravity in opposite directions respectively from the perpendicular to the horizontal, a 125

holding member vertically slidable on said fulcrum member and arranged to engage and releasably hold said supporting members in either the horizontal or the vertical position, a vertical coil spring supported at its lower end by said fulcrum member and supporting on its upper end said holding member and arranged to hold the latter in

the holding position, and a flexible plumb bob supporting member extending through said hole and attached to and arranged to withdraw said holding member from the holding position, substantially as set forth. 10

In testimony whereof I have signed my name to this specification.

MICHAEL J. LEARNIHAN.
